UNITED STATES PATENT OFFICE.

ALBERT DELAS, OF PARIS, FRANCE, ASSIGNOR TO DELAS CONDENSER CORPORATION, OF NEW YORK, N. Y., A CORPORATION OF DELAWARE.

JET CONDENSER.

Application filed January 24, 1920, Serial No. 353,866. Renewed October 14, 1925.

This invention relates to jet condensers. More specifically it relates to jet condensers adapted to be employed on the discharge or exhaust side of a vapor actuated motor such as a steam engine or turbine.

In practice jet condensers are provided with liquid-inlet openings of such size and configuration as to pulverize or atomize the condensing liquid. In order satisfactorily to perform this atomizing or pulverizing function these openings have been comparatively small with the result that they become clogged at times and therefore interfere with the continuous and efficient operation of the condenser. One of the objects of the present invention is to provide an arrangement in which these openings may be made large, freeing them from the tendency to become clogged, but in which the desired atomization or pulverization of the condensing liquid is effected nevertheless.

It has been common practice to provide a jet condenser with a pump, for example a centrifugal pump or a reciprocating pump, for removing the condensing liquid and liquid of condensation. In my invention the air or other gaseous fluid is removed from the condenser by means of a dry pump. This gaseous fluid usually contains more or less uncondensed vapor when it leaves the gas outlet of the condenser so that the maximum efficiency of the system is not attained. One explanation for this is that the efficiency of operation of a dry air pump is a direct function of the pressure of the air or fluid extracted from the condenser. Another object of the present invention is to provide means for freeing the gaseous fluid from steam or other condensable vapor before it leaves the condenser. Other objects and advantages will appear as the invention is hereinafter disclosed.

In the drawing I have illustrated what I now consider a preferred physical embodiment of my invention.

The jet condenser illustrated is provided with an inlet opening A for the steam or other vapor to be condensed. The water or other condensing liquid enters through the pipe B and is distributed in the annular space C whence it issues into the condensing chamber through orifices D of such size as will prevent clogging in the ordinary use of the device. Preferably the orifices D are arranged around the interior wall W of the

condensing chamber in a plurality of superimposed rows, as illustrated. Baffle means are provided for securing the desired atomization or pulverization of the jets issuing from the openings D into the condensing chamber. One form of such means is shown as comprising a plurality of rings E so shaped and so disposed that the incoming jets of water impinge against them and are not only pulverized and atomized but the stream of water issuing from each row of orifices is caused to converge towards the central portion of the condensation chamber. In this way an atomized or pulverized condensing liquid is obtained even though the orifices D are of large diameter. In order to facilitate cleaning of the last mentioned orifices the outer wall of the chamber C is preferably provided with hand holes providing easy access to the orifices. It will be noted that the inner wall W of the condensing chamber is removable and may be put in place without friction against the inner side of the outer wall of the condensing chamber. The condensing chamber discharges into a second and lower chamber from which the liquid is drawn off at P by any suitable means such as a centrifugal or reciprocating pump not shown.

While a large portion of the steam or other vapor which enters at A is condensed in the condensing chamber uncondensed steam enters the lower chamber together with the water and air. In order to remove or separate this vapor from the air or other non-condensable gas before the latter is drawn from the condenser, I provide within the lower chamber, preferably at the upper part thereof, a pan-like container shown in the form of an annular trough G. A small part of the liquid under pressure in the chamber C flows into the said container G through an opening H. An overflow opening I is provided for the trough G which opening serves not only as a liquid outlet for the trough but also as an opening through which the gaseous fluid in the lower chamber passes on its way to the gas outlet J. The latter may have connected thereto a dry air pump of the usual type. The passage of the last mentioned fluid is through the opening I over the thin film of water in the trough G (along two different paths), thence out through the outlet J. In passing over the thin film of water a large

portion, if not all, of the condensable vapor is condensed and thereby removed from the gaseous fluid.

It will be noted that the opening I is well above the level of the liquid in the lower chamber of the condenser even though the liquid may rise due to slowing up of the suction pump or the formation of too high a vacuum at low loads. Obstruction of the 10 said opening I is thus avoided.

What I claim is:—

1. A jet condenser comprising in combination a condensing chamber provided with a plurality of inlet openings for the condensing liquid, and annular baffle means against which the incoming liquid impinges and is directed towards the center of the chamber and across the path of the steam to be condensed.

20 2. A jet condenser comprising in combination, a mixing chamber provided with liquid-inlet and steam-inlet openings, a second chamber into which said mixing chamber discharges, a pan-like container within said second chamber, and means for conducting gaseous fluid from the upper part of the said second chamber, over said container and out of the condenser.

30 3. A jet condenser comprising in combination, a mixing chamber provided with liquid-inlet and steam-inlet openings, baffle means against which the incoming liquid impinges and is directed into contact with the steam to be condensed, a second chamber into which said mixing chamber dis-

charges, a pan-like container within said second chamber, and means for conducting gaseous fluid from the upper part of said second chamber, over said container and out of the condenser.

4. A jet condenser comprising in combination a casing, a chamber-defining wall removably mounted in the upper portion of said casing, said wall being provided with a plurality of relatively large liquid inlet 45 openings, means comprising a flange for deflecting and atomizing the streams which pass through said openings, and a pan surrounding the outlet of said chamber and over which the uncondensed gas must pass 50 in its exit from the condenser.

5. A jet condenser comprising in combination an outer casing, a wall within said casing cooperating with the latter to form a conduit for condensing liquid, said wall also defining the mixing chamber of the condenser and provided with a plurality of openings to enable the liquid in the conduit to be discharged into the mixing chamber, a second chamber into which said mixing chamber discharges, a pan-like liquid container provided with an overflow located between said chambers over which the gaseous fluid from the second mentioned chamber is 55 condensed, and means for conducting liquid 60 from the conduit to the container.

In testimony whereof I hereunto affix my signature.

ALBERT DELAS.
